[57] ABSTRACT

A breech block is mounted behind the breech in the frame of an explosively actuated tool and is movable transversely of the frame to an inoperative position exposing the rear end of the cartridge-receiving bore through the breech. A firing pin is supported by the block in line with the bore. Carried by the breech block for movement transversely thereof is a spring-pressed detent that normally projects into a hole in the frame beside the block to hold the block with its firing pin in operative position. The frame is provided with a second hole for receiving the detent when the block has been moved to its inoperative position. Manually operable means are mounted on the frame for pushing the detent out of either of the frame holes to permit it to be moved with the block to the other hole.

FIRING MECHANISM FOR EXPLOSIVELY ACTUATED TOOL

Many explosively actuated tools, such as cable cutters, have to be loaded and unloaded from the front end. This not only is a time consuming process, but it can be dangerous because of the possibility of accidental discharge of the cartridge.

It is among the objects of this invention to provide such a tool which can be loaded and unloaded from its rear end, which is provided with a firing pin that can be quickly moved laterally from operative to inoperative position, and which is simple in construction and operation.

The preferred embodiment of the invention is illustrated in the accompanying drawings, in which

FIG. 1 is a front view of the tool;

FIG. 2 is a side view shown partly in longitudinal section;

FIG. 3 is a cross section taken on the line 3—3 of FIG. 2; and

FIG. 4 is a view like FIG. 3, but with the firing pin in its inoperative position.

Referring to FIGS. 1 to 3 of the drawings, the metal frame 1 of the tool may be substantially rectangular in cross section and is provided with a passage extending through it from end to end. The major portion of this passage forms a barrel 2 for a projectile and has an anvil 3 screwed into its front end. Directly behind the anvil the opposite sides of the frame are cut away and the front of the frame is provided with a slot 4 that opens into the cable-receiving recess thus formed. To guide a cable 6 into the recess, the front of the frame is provided with an inclined guide finger 7. The rear end of the barrel forms the breech 8 of the tool, and the central bore 9 through the breech receives an explosive cartridge 10 that extends into a socket 11 in the rear end of a piston 12 that is slidably mounted in the barrel. The front end of the piston is tapered to form a cutting chisel 13. This piston-chisel is the projectile of the tool. It normally is held in position by a shear screw 14 projecting into the side of the piston from a hole in the front of the frame.

Directly behind the breech the frame is provided with a cylindrical opening 16 extending transversely through it from front to back. Slidably mounted in this opening is a breech block 17 that has a passage 18 through it aligned with the bore in the breech. Slidably mounted in the reduced front end of this passage is a firing pin 19. The rear end of this pin is provided with a head that is pivotally connected to the inner end of a lever 20 that extends outwardly through a notch 21 in the block and into a bore 22 through a portion of the breech block that projects from the back of the frame. The lever normally is locked by a removable safety pin 23. When, after this pin and another safety pin 24 have been removed, the outer end of the lever is struck by a spring-pressed hammer 25 carried by the tool in the usual way, the firing pin is driven forward against the cartridge to detonate it.

The breech block is held in its operative position just described by means of a pin 27 slidably mounted in a transverse passage 28 in the front or inner end of the block. The pin is urged outwardly by a coil spring 29, and its outer end projects into a hole 30 in the side of the frame beside the breech block.

It is a feature of this invention that the breech block can be moved out of the way to permit the tool to be loaded or unloaded from the back. In order to do this the locking pin 27 has to be removed from the frame hole so that the block can be pulled rearwardly part way out of the frame to expose the rear end of the cartridge or breech bore 9, as shown in FIG. 4. In its outer or inoperative position the locking pin snaps into another hole 32 in the side of the frame to lock the breech block in that position. A cartridge then can be inserted or removed through the open front end of passage 16 or, if desired, through a passage 33 (FIG. 2) in the rear end of the frame after the handle 34, which may be a pole, is unscrewed from the frame.

In order to unlock the breech block so that it can be moved lengthwise of frame opening 16, a stiff metal strip 36 is attached to the frame between the two holes 30 and 32 by

means of a screw 37. The screw extends through an enlarged opening in the strip, and the head of the screw is spaced from the frame a distance greater than the thickness of the strip. The strip is bent so that it can rock against the frame. Thus, when the breech block is in its normal or operative position shown in FIG. 3, the strip extends across the rear hole 32 in engagement with the frame, but immediately in front of the screw the strip is bent outwardly away from the frame so that it is inclined away from the other hole. Secured to the strip in line with the two holes are studs 38 and 39 that are small enough to enter the holes. While the breech block is in operative position, the rear stud 39 extends into hole 32 but most of the other stud is outside of the other hole because the inner end of that stud is engaged by locking pin 27.

When the upper end of strip 36 is pressed toward the frame, it causes the strip to rock and stud 38 to push the locking pin inwardly out of the front frame hole. Simultaneously, the strip pulls the other stud 39 out of hole 32. The outer end of the breech block then can be grasped to pull the block rearwardly in opening 16, which will cause the end of the locking pin to slide along the inside of the frame until it can snap into the rear hole to lock the block in its outer or inoperative position shown in FIG. 3. To reverse the block movement, the rear end of strip 36 is pressed toward the frame to push the locking pin out of hole 32 so that the block can be pushed forward. The inner surface of the frame is provided with a groove 41 extending between the two frame holes for receiving the outer end of the locking pin. This permits the studs to push the pin completely out of the frame holes without the studs entering breech block passage 28 and keeping it from being shifted. The projection of the pin into the groove also prevents the breech block from turning out of position while it is being moved back and forth when there is no cartridge head engaging the adjoining flattened area of the block. It also avoids any likelihood of the block being pulled entirely out of the frame.

According to the provisions of the patent statutes, I have explained the principle of my invention and have illustrated and described what I now consider to represent its best embodiment. However, I desire to have it understood that, within the scope of the appended claims, the invention may be practiced otherwise than as specifically illustrated and described.

I claim:

1. An explosively actuated tool comprising a frame provided with a barrel having a breech with a cartridge-receiving bore therethrough, a breech block mounted in the frame behind said breech, a firing pin supported by the block in line with said bore normally, means for actuating the pin, the block being movable transversely of the frame to an inoperative position exposing the rear end of said bore, a detent carried by the block for movement transversely thereof, a spring urging the detent outwardly of the block, said frame being provided beside the block with a hole therethrough into which said detent normally projects to hold the block in operative position, the frame being provided with a second hole for receiving the spring-pressed detent when the block has been moved to said inoperative position, and manually operable means mounted on the outside of the frame for pushing said detent inwardly out of either of said holes to permit it to be moved by the block to the other hole, said manually operable means including a first member normally substantially engaging the outer end of said detent in the first hole and projecting from the frame, a second member extending into the second hole, and means connected to the outer ends of said members for withdrawing the second member from the second hole as the first member is pushed into the first hole to push said detent out of that hole.

2. A tool according to claim 1, in which said first and second members are studs and said connecting means is a stiff member movably connected to the frame.

3. A tool according to claim 1, in which said detent is a longitudinally movable pin slidably mounted in the breech block and said frame is provided with a groove connecting the inner ends of said holes and receiving the outer end of said pin while it is moving from one of the holes to the other.

4. A tool according to claim 2, in which said stud connecting stiff means is a bowed metal strip with the studs fastened to its opposite ends and provided with a central opening, the tool including a fastening member mounted in said frame and extending loosely through said strip opening to permit the strip to be rocked, whereby to swing one of the studs outwardly of a frame hole and to simultaneously swing the other stud in-

wardly of the other hole to push said detent out of that hole.

5. A tool according to claim 2, in which said stud connecting stiff member has a central portion rockable on the frame, the tool including means connecting said central portion to the frame.
